UNITED STATES PATENT OFFICE.

JOHN B. KENISON, OF LYNN, MASSACHUSETTS.

SOLE-EDGE-BLACKING MACHINE.

SPECIFICATION forming part of Letters Patent No. 629,132, dated July 18, 1899.

Application filed July 9, 1898. Serial No. 635,506. (No model.)

To all whom it may concern:

Be it known that I, JOHN B. KENISON, of Lynn, county of Essex, State of Massachusetts, have invented an Improvement in Sole-Edge-Blacking Machines, of which the following description, in connection with the accompanying drawings, is a specification, like letters and numerals on the drawings representing like parts.

This invention relates to apparatus for applying blacking or other coloring-matter to the edges of boot and shoe soles, whereby the coloring-matter is absolutely prevented from touching the upper or the projecting top of the sole when desired, the coloring-matter being applied rapidly and evenly without spattering.

My present invention has for one of its objects the improvement of this class of apparatus in general, and more particularly it is an improvement on the apparatus forming the subject-matter of an application, Serial No. 635,010, filed May 4, 1897, by myself and others as a joint invention.

I make use herein of a rotatable color-applying device having a continuous slightly-yielding periphery, as in said application referred to, the coloring-matter being suitably applied to said device and transferred thereby to the work.

The various novel features of my invention will be hereinafter described in the specification and particularly pointed out in the claims.

Figure 1, in front elevation, represents an apparatus embodying my present invention. Fig. 2 is a rear elevation thereof. Fig. 3 is a side elevation, enlarged, of the base of the supporting standard or column for the apparatus. Fig. 4 is a top or plan view of the base of the column being shown in section. Fig. 5 is an enlarged vertical section of one of the color-reservoirs—viz., the lower inner reservoir, Fig. 1. Fig. 6 is a transverse section thereof on the line $x-x$, Fig. 5. Fig. 7 is a like view on the line $x'-x'$, Fig. 5, looking down. Fig. 8 is a section on the line $x''-x''$ looking up. Fig. 9 is a sectional detail to be described, taken on the line x^2-x^2 , Fig. 7. Fig. 10 is a side elevation of the guard or

shield shown in section Fig. 5. Fig. 10^a is a vertical section on the line x^3-x^3 , Fig. 10. Fig. 11 shows in perspective details of the means for controlling the passage of coloring-matter from the reservoir. Fig. 12 is a transverse sectional detail on the line $y-y$, Fig. 5, through the chambered boss in the reservoir; and Fig. 13 is a vertical sectional view on the line x^8-x^8 , Fig. 1, looking to the right.

Referring to Figs. 1 and 2, the head of the apparatus comprises a frame A of suitable shape to support the various working parts and preferably mounted on a standard or column A', having a base A², Figs. 3 and 4, adapted to be secured to the floor or other support. The frame is provided with bearings a for the main driving-shaft B, having fast thereon a gear C in mesh with an intermediate pinion B⁶, mounted on the frame, said pinion in turn meshing with a gear B⁵, fast on a second shaft B⁴, rotatable in bearings a^x on the frame. (See Fig. 2.) A suitable clutch is mounted on the shaft B, the member B' being fast thereon, while the loose member B² is shown as a cone-pulley, retained on the shaft 75 by a collar b^x , the clutch members being thrown out of engagement by means of a tripping device, comprising a trigger b^4 on the member B', a co-operating spring-controlled stud b^7 , mounted on an arm b^6 , fast on a rock-shaft b^5 , having bearings in the frame A, and provided with an actuating-handle b^8 , moved by the operator. This clutch mechanism forms no part of my present invention and need not be further described herein, as any 80 other suitable clutch device may be used.

The color-transferrer is herein shown as a truncated cone T, preferably made of rubber, having a continuous slightly-yielding periphery to apply the color to the work smoothly 90 and evenly without streaking or spattering.

The edge of the sole is held by the operator against the rotating transfferer, which, as shown in Fig. 5, is applied to the reduced end B⁸ of the main shaft, its inner end abutting against a collar or flange 2, while it is held in place on the shaft by a washer 3, secured by a screw 4 to the reduced portion of the shaft. The shaft B⁴ also has a like transfferer T secured thereto, each transfferer hav- 100

ing its own reservoir for the "coloring-matter," which term includes blacking, so that one machine can do the work of two separate ones, a different color being taken from each reservoir, if desired.

As the two reservoirs D and E differ somewhat in some of the details of construction, they will be described separately, the reservoir D coöperating with the transferer T and being shown in section, Fig. 5, with details in Figs. 6 to 11. Yokes $a^{16} a^{17}$, mounted on the frame A, engage the upper ends of the reservoirs D and E, respectively, to steady them, the reservoir in each case consisting of a cylinder open at its ends, with apertured tops $D^X E^X$, respectively.

The reservoir D is shown as threaded at its lower end to screw tightly onto an upturned annular flange d on the bottom plate D' , which latter has an extension D^2 , provided with a boss d' , a screw-bolt d^2 extending through the boss entering a horizontal notch d^X in the frame, (see Fig. 2,) a thumb-nut d^3 at the other end of the bolt serving to clamp the bottom plate securely in place. Within the flange d an elongated hub or boss d^4 is erected on or forms part of the bottom plate D' , divided by a vertical partition d^5 , Figs. 5 and 6, into two cylindrical open-ended chambers, the front wall of the boss having a transverse inlet-opening d^6 , Fig. 6, through which the coloring-matter passes from the reservoir to the interior of the boss. A tubular plug d^7 , (see Fig. 11,) closed at its upper end and having an inlet-port d^8 , adapted to register with the opening d^6 of the boss, is inserted in the right chamber of the latter, Fig. 5, and is rotatably held therein by a stop 5, (see Fig. 12,) the edge of which partially enters an annular groove d^9 in the plug, the stop being inserted in a recess made in the partition-wall d^5 and held securely in place by a setscrew 6. In order to conveniently rotate the plug d^7 , I provide the lower end thereof with a suitable handle d^{10} , by which the operator can turn the plug to expose more or less of the port d^8 adjacent the inlet-passage d^6 in the boss d^4 , and by reference to Fig. 6 it will be obvious that by movement of the handle d^{10} in the direction of the arrow the size of the inlet to the interior of the valve d^8 may be reduced to the desired extent or altogether closed. The valve proper is shown as an open-ended tube d^{12} , inserted to oscillate in the plug d^8 and having attached to its lower end a segment-gear d^{13} , which meshes with a circular rack R, as herein shown, said tube d^{12} having a port d^{14} , (see Fig. 11,) which is at the height of the inlet-port d^8 of the plug, the oscillation of the tube causing the port d^{14} to move back and forth from the inlet-port, so that the passage of the coloring-matter to the interior of the tube is intermittent. A guard 8, shown as a flat metal arm, Fig. 8, is pivotally mounted at 9 on a lug 10 of the bottom plate D' and is adapted to be swung

in under the rear end of the segment-gear d^{13} to hold the tube d^{12} in place, the guard being retained in position by springing it between two opposed pins 12 and 13.

The transferer T is located below the reservoir D and the coloring-matter is conducted to the transferer by a distributer f, shown as a block having a longitudinal chamber f' open along its under side at f^2 immediately above the transferer. A slide-rod f^3 is longitudinally movable in the chamber to vary the length of the opening f^2 , and thereby control the width of the band of color on the transferer. The distributer has a groove f^4 in its top to be entered by the end of a screw-stud 14, threaded into the bottom plate D' , a catch f^5 on the distributer being movable into a groove 15 in the stud to retain the distributer thereon. A hollow stem f^6 , secured to the latter, enters snugly the valve d^{12} , the lower end of the stem opening into the chamber f' , while a hole f^7 in the stem is at a level with the port d^{14} . An evener-blade f^8 is attached to the side of the distributer by a screw 16 to smooth the film of color on the transferer and prevent an undue thickness of the film as it is applied to the work, adjustment being effected by means of the attaching-screw. The coloring-matter passes from the reservoir through the slot d^6 , ports d^8 and d^{14} , and hole f^7 into the hollow stem f^6 , and thence down the latter into the chamber f' and onto the transferer through the delivery-opening f^2 of the chamber.

The means for effecting the passage of the coloring-matter from the reservoir E to the transferer T' is substantially the same as has been described for the reservoir D, with the exception, however, that the boss e^4 , provided with an inlet-slot e^6 , has but one chamber and is made substantially cylindrical in shape to receive a plug e^7 in every respect similar to the plug d^7 and provided with a regulating handle or arm e^{10} , while a tubular valve similar to the valve d^{12} is inserted within the plug, said tubular valve having a segment e^{13} (see Fig. 2) in mesh with a rack Q. The distributer g is in its general construction like the distributer f—that is to say, it is chambered, with a longitudinal slot in the bottom of the chamber to deliver the coloring-matter to the transferer T', said coloring-matter passing from the interior of the valve mechanism to the distributer by means of a hollow stem g^6 ; but I have herein shown the distributer g as provided with two slide-rods g^3 and g^{30} , located in the opposite ends of the distributer and coöperating with two scraping or evener blades g^8 and g^{30} , respectively, which coöperate with the transferer, as before described, as by such construction I am enabled to control the flow of the coloring-matter independently at the outer end of and for the main body portion of the transferer. The bottom plate E', having a boss e' , held in place on the frame by a bolt e^2 , having a thumb-

nut e^8 , and the screw-stud 140 to support the transerrer g are all substantially similar to the corresponding parts for the reservoir D.

When using the transerrer T' to apply color, the bottom of the sole of the boot or shoe is conveniently held against a roll or truck 35, mounted on a threaded arm 36, screwed into a bracket A⁸, forming part of the frame, and held in adjusted position by a check-nut 37.

When the machine is stopped, it will be obvious that all communication between the reservoir and the distributer may be shut off by swinging the arms d^{10} or e^{10} to close the inlet-ports in the plugs d^7 or e^7 , respectively.

In operation more of the coloring-matter must be delivered to the transerrer when it is thick than when it is thin, so that in the former case the valve mechanism is adjusted to permit a greater inlet-passage from the reservoir to the hollow stem leading to the distributer than would be the case were the coloring-matter thin.

The racks Q R are secured, respectively, to slide-rods q^r , which slide in suitable bearings $q^x r^x$ on the bottom plates of the reservoirs, and said rods are provided, respectively, with adjustable stop-collars $q' r'$ between the bearings, and outside of the bearings spiral springs $s s'$ surround said rods between the inner bearings (see Fig. 1) and collars $q^2 r^2$, adjustably secured to the slide-rods, so that the tension of the springs may be regulated, the latter normally acting to hold the racks in the position shown in Figs. 1 and 2, with the openings in the ports in the tubes attached to the segmental gears in such position as to close communication between the interior of said tubes and the reservoirs, thus automatically effecting a stoppage of the flow of the coloring-matter when the machine is not in operation.

In order to reciprocate the slide-rods q^r when the machine is in operation, I have mounted an inclined rock-shaft h in bearings on brackets 40 and 41 on the main frame, the shaft being provided at its upper end with an adjustably-attached arm h^4 opposite the inner end of the rack-carrier q , while collars 42 and 43, fast on the rock-shaft between its bearings, limit its longitudinal movement in the latter. A sleeve h' is loosely mounted on the rock-shaft above the collar 42 and has a rearwardly-extended arm h^2 , (see Fig. 2,) which is pivotally connected to a link m , the latter at its lower end (see Figs. 3 and 4) being pivoted to a lever m^x , fulcrumed at m^o on a plate M, adapted to be secured to the floor alongside of the base A² of the standard, said plate having upturned ears $m^2 m^3$, on which are fulcrumed at m^4 and m^5 , respectively, treadles M' M², respectively, the forward ends of the treadles extending beneath the lever m^x at opposite sides of its fulcrum. By depressing the treadle end of the treadle M' the link m will be drawn down, and by a similar movement of the treadle M² the said link

will be raised, and thereby the sleeve h' will be lowered or raised, respectively. As shown in Fig. 2, the link is provided with collars 70 50 and 51, and between the collars and a fork 52 on the standard A' are mounted spiral springs $s^8 s^4$, the said springs tending to maintain the treadles in normal position and the rock-shaft in substantially the position 75 shown in Figs. 1 and 2. Hubs n and o are mounted on the rock-shaft h adjacent each other and preferably with spiral springs s^5 and s^6 between said hubs and the collar 43 and arm h' , the hub n being fast on the rock-shaft and having a forwardly-extended arm n' provided with preferably a roll n^2 , and the hub o has also a forwardly-extended arm with an attached roller o^2 , said rolls being adapted to be moved (one or the other of them) into the 80 path of a cam H, fast on the shaft B. If the operator places his foot on the treadle M², the rock-shaft h and the parts mounted thereon will be lifted to bring the roll o^2 into the path of said cam, whereas operation of the treadle 85 M' depresses the rock-shaft and its parts to bring the roll n^2 into the path of the cam, the normal position of said rolls $n^2 o^2$ being out of the path of movement of the cam. Now when the roll n^2 is in the path of the cam each 90 rotation of the main shaft will operate through said roll and the arm n' to rock the shaft h , and thereby the arm h^4 , to the left, viewing Fig. 1, so that the rack-carrier q will be moved to the left against the action of its spring s , 100 the latter effecting the return movement of the rock-shaft as the cam passes beyond the roll n^2 . Similarly if the roll o^2 is in operative position the rack-carrier r will be moved against the action of its spring s' , the latter 105 returning the arm o' to normal position or acting to maintain its roll o^2 in the path of the cam, the hub o being loosely mounted on the rock-shaft, and it will be noticed in Fig. 1 that the arm o' is provided with a flattened 110 face o^8 opposite the rack-carrier r . If the transerrer T' is in use, the valve mechanism thereof will be operated through the arm h^4 and rack-carrier q , whereas if the transerrer T is in use the valve mechanism for the reservoir D will be operated by or through the arm o' , and it will be noticed that the mechanism is so arranged that the valve mechanism of only one reservoir can be automatically operated at a time. 115

As the coloring-matter will not be thrown or spattered from the transerrer, it is unnecessary to use a shield, but a guard is requisite to protect the shoe-upper, and I have herein provided a guard which at the same 120 time can effect the application of the coloring-matter to the top portion of the sole extended beyond the upper, if desired.

Referring to Fig. 5, the left-hand chamber of the boss d^4 is provided with a plug c^7 , having an inlet-port c^8 , and said plug at its upper end is threaded to receive an adjustable cap c , closing the upper end of the plug and extending beyond or above the boss d^4 . With-

in the plug is arranged a hollow tube c^{12} , having a port c^{14} (see Fig. 6) and at its lower end a segmental gear c^{13} in mesh with the rack R , said gear and tube being held in place by the plate 8 , hereinbefore described. The guard k is shown as a flat plate having a convexed lower end k' and at its outer side a chamber k^2 with a vertical outlet near its lower end, as at k^3 , Figs. 10 and 10^a, the said outlet opening on the flat face of the guard-plate k , which latter is depressed at k^4 to permit the coloring-matter to flow thereover. The chamber k^2 has attached to its upper end a long hollow stem k^5 , which is extended up into the tube d^{12} , said stem having, as shown in Fig. 10, an elongated opening k^6 therein to register with the openings c^8 and c^{14} . I have herein shown the upper end of the stem (see Fig. 5) as provided with a screw-cap k^7 , the head of which projects over the upper end of the tube c^{12} and thereby prevents withdrawal of the guard-stem, and between the screw-cap and the top of the adjustable cap c of the plug is interposed a suitable spring S , which normally presses the guard downward, the tension of the spring being adjusted by means of the cap c . The stem k^5 has secured thereto a collar k^8 , which is adapted to rest against the head of a stop-screw k^9 , threaded into the bottom plate D' and held in adjusted position by a set-screw k^{10} . By varying the position of the head of the stop-screw the downward movement of the guard under the influence of the spring S is regulated, and it will be seen from the drawings that the guard itself is located immediately adjacent but not in contact with the outer end of the transerrer T . The opening k^6 in the hollow stem is elongated in order to provide for the longitudinal movement of the stem in the tube c^{12} . The coloring-matter flows onto the inner face of the guard-plate at k^4 , which when in use enters between the upper and the sole, coloring-matter flowing from the guard onto the top of the sole, while the edge of the latter has color applied thereto from the transerrer T . The plate itself prevents the coloring-matter from passing onto the upper by the construction herein shown, and the guard also acts as a guide for the operator in manipulating the shoe.

When the shoe is held with the edge of its sole against the transerrer, the combined guard and guide plate k will be pushed upwardly a distance corresponding to the width of the exposed top portion of the sole. The guard-plate is held in parallelism with the outer end of the transerrer T by means of a slotted plate 60 , secured to the bottom plate D' , the rear part of the plate entering and moving up and down in the slot 61 . (See Fig. 2.) The guard is used for plain work and about the shank of the boot or shoe; but if fairstitch-work is being handled not only must the upper be protected, but also the stitching at the top of the sole, and in doing such work the handle e^{10} is turned to close the communi-

cation between the ports c^8 and c^{14} , so that the coloring-matter cannot pass from the reservoir into the chamber of the guard-plate. 70 The operator holds the boot or shoe with the edge of the sole pressed up against the edge of the rotating transerrer and with the edge of the guard-plate in the crease between the sole and the upper, so that the transerrer 75 will apply the coloring-matter evenly and rapidly to the sole edge as it is turned to present new portions thereto, the guard-plate effectually protecting the upper, the movement of the boot or shoe being toward the operator. 80

The term "coloring-matter" herein used includes blacking or other coloring-matter or stain which is to be applied to the edge or the upper portion of a boot or shoe sole.

Having fully described my invention, what 85 I claim, and desire to secure by Letters Patent, is—

1. In an apparatus of the class described, a rotatable color-transerrer, an adjacent reservoir, a bottom plate therefor having an 90 aperture, a tubular plug extended through said aperture and having an inlet-port within the reservoir, a tube adapted to oscillate in the plug and having an inlet-port, a feed-stem leading from said tube, and means to 95 oscillate the latter, to intermittently open and close its inlet-port, substantially as described.

2. In an apparatus of the class described, a rotatable color-transerrer, an adjacent reservoir, having a hollow boss therein provided 100 with an inlet, a hollow feed-stem to convey the coloring-matter from the reservoir to the transerrer, and valve mechanism within the boss, to control the passage of coloring-matter into the feed-stem, substantially as de- 105 scribed.

3. In an apparatus of the class described, a rotatable color-transerrer, an adjacent reservoir, a plug-valve therein to control the passage of coloring-matter from the reservoir 110 to the interior of the valve, an oscillating tube in said valve, provided with an inlet-port, a stationary feed-stem extended into the tube and having an inlet-port, and means to oscillate the said tube, to intermittently 115 bring its port opposite the port of the feed-stem, substantially as described.

4. In an apparatus of the class described, a rotatable color-transerrer, an adjacent reservoir, a plug-valve therein to control the pas- 120 sage of coloring-matter from the reservoir to the interior of the valve, an oscillating tube in said valve, provided with an inlet-port, a stationary feed-stem extended into the tube and having an inlet-port, a distributor at the 125 lower end of the stem and immediately above the transerrer, to convey coloring-matter thereto, and means to oscillate said tube and bring its port into intermittent register with the port of the stem, substantially as de- 130 scribed.

5. In an apparatus of the class described, a rotary color-transerrer, a reservoir for the coloring-matter, a detachable chambered dis-

- tributer having a hollow stem communicating with the reservoir, the distributer having its delivery-opening immediately above the transferrer, means to control the passage of the color from the reservoir to the hollow stem and thence to the transferrer, independent means to vary the length of the delivery-opening of the distributer, and means, including a catch, to connect the distributer and reservoir, substantially as described.
6. In an apparatus of the class described, a rotary color-transferrer, a reservoir for the coloring-matter, a chambered distributer communicating with the reservoir, and having its delivery-opening immediately above the transferrer, means to control the passage of the color from the reservoir to the transferrer, and a scraper-blade to coöperate with the periphery of the transferrer and regulate the film of color thereon, substantially as described.
7. In an apparatus of the class described, a rotary color-transferrer, a reservoir for the coloring-matter, having an outlet, means to regulate the effective opening thereof, concentric feed and valve tubes within the reservoir and having each an inlet-port, and means to intermittently bring said ports into register opposite the outlet of the reservoir, to permit the entry of coloring-matter to the feed-tube, substantially as described.
8. In an apparatus of the class described, a rotary color-transferrer, a reservoir for the coloring-matter, a fixed, chambered distributer located above the transferer and having an elongated delivery-opening, means to vary the length of said opening, and connections between the reservoir and distributer, to convey coloring-matter to the latter, substantially as described.
9. In an apparatus of the class described, a rotary color-transferrer, a reservoir for the coloring-matter, having an outlet, means to regulate the effective opening thereof, concentric feed and valve tubes within the reservoir and having each an inlet-port, means, including a rack-and-segment gear, to intermittently bring said ports into register opposite the outlet of the reservoir, a spring-controlled rack-carrier, and means to move the rack-carrier in one direction, the spring moving it in the opposite direction, substantially as described.
10. In an apparatus of the class described, a conical, rotatable color-transferrer having a yielding and continuously-coherent periphery, against which the edge of the sole to be colored is held, a chambered color-distributer having an elongated delivery-opening above and adjacent the transferrer, means to regulate the length of the opening, and an adjustable blade to regulate the film of color on the transferrer, substantially as described.
11. In an apparatus of the class described, a plurality of color-transferrers, a reservoir and a distributer for each, means to control the passage of the coloring-matter from each reservoir to its distributer, and including a rack and gear, independent reciprocable rack-carriers, rocker-arms, one to coöperate with each carrier, an actuating-cam for said arms, and means to effect the operation of either arm by the cam, substantially as described.
12. In an apparatus of the class described, an open-ended reservoir, a bottom plate therefor having a threaded annular flange to engage the lower end of the reservoir, a hollow boss on the upper side of the bottom plate within the reservoir, and means supported wholly by said bottom plate and partly within the boss, to control the delivery of coloring-matter from the reservoir, substantially as described.
13. In an apparatus of the class described, a rotatable transferrer having a yielding, continuously-coherent periphery, a yieldingly-mounted upper guard adjacent the outer end of the transferrer, the lower edge of the guard serving as a guide to enter the crease between the sole and upper of a boot or shoe, and means to convey coloring-matter to the guard and transferrer independently, substantially as described.
14. In an apparatus of the class described, a rotatable transferrer, means to convey coloring-matter thereto, to be transferred to the edge of a boot or shoe sole, a yieldingly-mounted upper guard near but out of contact with the outer end of the transferrer and having an attached chamber, an outlet for the chamber opening on the inner face of the guard, and means to convey coloring-matter to said chamber, substantially as described.
15. In an apparatus of the class described, an upper guard having a flat inner face with a depressed portion near its lower edge, and a color-chamber forming a part of said guard and having an outlet-opening on the depressed portion thereof, the thin, convex lower edge of the guard forming a guide for the boot or shoe, the coloring-matter being conveyed over the inner face of the guard to the exposed top of the sole, substantially as described.
16. In an apparatus of the class described, a reservoir for the coloring-matter, an upper guard provided on its outer side with a color-chamber having an outlet on the inner side of the guard, a hollow feed-stem attached to said chamber and extended into the reservoir, means to support the guard, and means to control the passage of coloring-matter from the reservoir to the feed-stem, substantially as described.
17. In an apparatus of the class described, a reservoir for the coloring-matter, an upper guard provided on its outer side with a color-chamber having an outlet on the inner side of the guard, a hollow feed-stem attached to said chamber and extended into the reservoir, adjustable means to yieldingly support the guard, valve mechanism to control the passage of coloring-matter from the reservoir to the feed-stem, and a stop to limit the movement of the guard, substantially as described.
18. An upper guard having a thin lower edge

to enter the crease between the upper and sole of a boot or shoe, a color-chamber on the outer side of the guard, and an upright outlet for said chamber, located near the lower edge of 5 and opening on the inner face of the guard, substantially as described.

In testimony whereof I have signed my

name to this specification in the presence of two subscribing witnesses.

JOHN B. KENISON.
